UNITED STATES PATENT OFFICE.

MARY F. DEVENNIE, OF PHILADELPHIA, PENNSYLVANIA.

DESIGN FOR A BED-PAN.

SPECIFICATION forming part of Design No. 32,989, dated July 24, 1900.

Application filed June 28, 1900. Serial No. 21,666. Term of patent 14 years.

To all whom it may concern:

Be it known that I, MARY F. DEVENNIE, a citizen of the United States, residing at 1340 Lombard street, in the city of Philadelphia and State of Pennsylvania, have invented and produced a new and original Design for Bed-Pans, of which the following is a specification, reference being had to the accompanying drawings, forming part thereof.

10 Figure 1 is a perspective view of a bed-pan, showing my new design. Fig. 2 is a side view of the same. Fig. 3 is a transverse sectional view on line 3 3, Fig. 2.

As shown in the drawings, the leading or material feature of my design consists of a curved base or bottom A, as shown in Figs. 2 and 3, having its largest or deepest portion at the

point C directly opposite the opening D, a broad flat surface on the upper side of the bed-pan, and a spout or neck with the interior opening larger than the exterior opening.

Having described my invention, what I claim as new, and desire to secure by Letters Patent, is—

The design for a bed-pan, as herein shown and described.

In witness whereof I have signed my name to this specification in the presence of two subscribing witnesses.

MARY F. DEVENNIE.

Witnesses:

WM. J. SKEEN,
WM. F. DONNELLY.
